UNITED STATES PATENT OFFICE.

ROBERT W. GRAHAM, OF YORK, PENNSYLVANIA.

CONVERTIBLE WAISTBAND.

1,017,535.

Specification of Letters Patent. Patented Feb. 13, 1912.

Application filed March 30, 1911. Serial No. 618,014.

To all whom it may concern:

Be it known that I, ROBERT W. GRAHAM, a citizen of the United States, residing at York, in the county of York and State of Pennsylvania, have invented certain new and useful Improvements in Convertible Waistbands; and I do declare the following to be a full, clear, and exact description of the invention, such as will enable others skilled in the art to which it appertains to make and use the same.

This invention relates to improvements in waist bands, more especially in waist bands for trousers.

These garments as now constructed are either made "full length" for use with suspenders or "short length" for use without suspenders and with or without a belt as may be desired. Short length trousers are made to hang from the hips of the wearer and the waist band is positioned a little nearer the crotch than those which are made full length for use with suspenders. Full length trousers cannot be comfortably worn without suspenders because they necessarily drop and become too long when not so supported or if they are tightened by buckles or the like, which are ordinarily used, they present an unsightly appearance at the waist by reason of the formation of folds or plaits which latter also render the garment uncomfortable.

The primary object of the invention is to provide a waist band for a garment of this character constructed to enable said garment to be quickly and easily converted into either "full length" or "short length" trousers, and either form into which the garment is converted will present the same appearance and afford all the comforts of the form which it represents.

Another object of the invention is to provide a convertible waist band which may be used either with suspenders or with a belt and when used with a belt the suspender supporting buttons are invisible and when used with suspenders the belt holding straps are out of sight.

Another object is to provide a convertible waist band for use with suspenders or with a belt which is formed as a continuation of

the upper portion of the trousers and which may be used to vary the length of the trousers.

With these and other objects in view, the invention consists of certain novel features of construction, combination and arrangement of parts as will be more fully described and particularly pointed out in the appended claims.

In the accompanying drawings: Figure 1 is a perspective view of the upper portion of a pair of trousers equipped with this improved band arranged for use with suspenders; Fig. 2 is a rear elevation with the band arranged for use with a belt; Fig. 3 is a transverse section taken on the line 3—3 of Fig. 2; Fig. 4 is a similar view taken on the line 4—4 of Fig. 1.

In the embodiment illustrated a pair of trousers 1 is shown with the material of the upper portion extended for about two inches, more or less, beyond the ordinary waist line of the trousers to form a waist band of the desired width. This extension 2 is folded inwardly and lined with a suitable strip 3 of stiffening canvas which is slightly narrower than the extension 2, with its inner edge disposed at the junction of said extension, with the upper edge of the garment and stitched intermediately of its width at a point below the longitudinal median line thereof to the material forming the trousers top whereby the folding of the band at the line of stitching 3^a will slightly lengthen or shorten the distance between the crotch and the extreme top edge of the trousers, which distance or length is known in the art as the "rise." A lining strip 4 of any suitable material is arranged on the outer face of said stiffening strip 3 and stitched to the trousers top at a point about one inch from the fold of the member 2. A depending lining strip or skirt 5 is also stitched with said strips 3 and 4 to the trousers and extends below the free edge of the extension 2 forming a reinforcing member at the waist of the trousers.

The free edge of the extension 2 is preferably folded inwardly over the lower edge of the reinforcing or stiffening strip 3 and the free edge of the lining strip 4 is turned in

and blind stitched to the outer face of the inturned edge of the extension 2 as is clearly shown in Fig. 3.

The extension 2 is preferably but not necessarily provided with a plurality of transversely extending longitudinally spaced belt receiving loops as 6 which may be formed by stitching strips as 7 to the outer face of the member 2 or by forming transverse slits 10 as 8 therein, said slits being preferably formed in the seams of the trousers. One end of this extension 2 is arranged flush with the inner edge of the fly of the trousers and is secured thereto for about one-half of 15 its width, the free lower end thereof being provided with a fastening element such as a hook 9 for engagement with a coöperating element formed on the other end of the band or extension 2. This last mentioned end of 20 the extension or band 2 extends flush with the opposite edge of the front opening in the trousers and is secured to said edge by stitching in the usual manner. The lower corner of this end of the band is cut away 25 to form a recess 10 the coöperating fastening element 11 in the form of an eye being secured to the inner wall of said recessed portion to provide for the overlapping of the ends of the band, the end having said 30 recess being preferably provided with a button hole and the opposite end with a button in the ordinary manner.

A plurality of buttons as 12 are secured to the upper edge of the trousers adjacent 35 the line of folding of the extension 2 and are positioned in the usual places for attachment of the suspenders, the row of stitching 3^a being below the buttons as clearly shown in Fig. 1.

40 When the trousers are to be used without suspenders as shown in Figs. 2 and 3 the extension 2 is turned outwardly, being folded downwardly at the line of stitching 3^a above referred to, with a portion of said 45 extension projecting above the top of the trousers and the other portion depending thereover, forming a neat looking band for the application of a belt if desired.

It will thus be observed that the turning 50 over of the band or extension 2, to provide for the use of the garment without suspenders and either with or without a belt as may be desired, shortens the "rise" or distance between the crotch and the top edge 55 of the garment, and at the same time disposes an additional thickness of cloth within the band between it and the wearer, thereby assisting in holding the trousers in position without the use of buckles or the 60 like, and without any plaits or gathers at the waist. In this connection, it may be observed that the internal diameter of the extreme top of a pair of "full length" trousers is slightly less than their diameter at 65 the waist line, which is just above the hips,

and consequently when the band or extension 2 is turned down on the outside, said band will more snugly fit the waist of the wearer and support the trousers in proper position on the body. A further advantage 70 of this tightening of the waist portion of the garment by reason of the turning down of the band or extension 2, resides in the fact that a leather or other extraneous belt is rendered unnecessary, although of course, 75 such a belt may be used if desired. When an additional belt is used, straps 3 or other belt retaining or supporting devices are employed on the band, but in some embodiments of the invention it is preferred to 80 omit the belt supporting or holding means.

It is well known that when a person wears suspenders on the ordinary trousers no trouble is experienced with the fit at the waist, crotch or length but if he wears a belt 85 and removes his suspenders the trousers will be too large at the waist will slip down on the hips and sag in the crotch and be too long in the legs and to make them fit at the waist and hips it is necessary to buckle them 90 in at the waist line which causes plaits to be formed at the side or back. If the trousers are made sufficiently short to wear with a belt, suspenders cannot then be used comfortably with the same trousers. 95

Trousers constructed with this improved waist band can readily be worn with suspenders by fastening them to the buttons 12 thereon with the belt loops or slots disposed inside the trousers out of sight as shown in 100 Fig. 1. When a belt is to be worn with the suspenders removed, the waist band is reversed to bring the belt loops and slots on the outside and to dispose the buttons underneath said band out of sight. 105

When arranged for use without suspenders or with a belt the lining strip 4 extends upwardly and the strip or skirt 5 downwardly thereby forming a smooth flat surface on the inner face of the waist of the 110 trousers and affording comfort to the wearer.

While one embodiment of this invention has been illustrated in the drawing and specifically described in the specification, it 115 will be understood that the invention is not limited to the construction disclosed since changes and variations may be made, such for example, as making the band or extension 2 from a separate piece or pieces of material, instead of integral with the body of the garment, and other such changes as may be within the spirit and scope of the invention. 120

I claim as my invention:

1. A garment having a convertible waist band secured intermediate its width to said garment at the upper end thereof and suspender attaching means on one face of said band. 125

2. A garment having a convertible waist band comprising a member secured immediately of its width to said garment at the upper end thereof, suspender supporting elements secured to one face of said band and belt supporting means on its other face.
5 In testimony whereof I have hereunto set

my hand in presence of two subscribing witnesses.

ROBERT W. GRAHAM.
